UNITED STATES PATENT OFFICE.

DANIEL H. MURPHY, OF HARTFORD, CONNECTICUT.

DESIGN FOR A GLOVE.

SPECIFICATION forming part of Design No. 31,163, dated July 4, 1899.

Application filed May 24, 1899. Serial No. 718,119. Term of patent 7 years.

To all whom it may concern:

Be it known that I, DANIEL H. MURPHY, a citizen of the United States, residing in Hartford, in the county of Hartford and State of Connecticut, have invented and produced a new and original Design for Gloves, of which the following is a specification.

This invention relates to gloves the finger-tips of which will when shaped in conformity therewith possess distinguishing features resembling and imitating more particularly the perfect form of the finger-nails, so that a certain characteristic appearance and elegance will result.

15 In the drawings, Figure 1 represents a glove, showing my new design. Fig. 2 is a section on line 2 2, Fig. 1.

As shown in the drawings, the leading or material feature of my design consists of a 20 representation or formation of the finger-tips to resemble finger-nails, the particular form required being permanently imparted to the tips by stamping or otherwise.

In Fig. 2 is represented one of the finger-tips in longitudinal section, showing the manner in which the contour of the finger-nails is produced and having the nail portion 10 and the depression 11, the latter following the perfect shape of a finger-nail near the root thereof and serving to impart to the finger-tip an appearance which is true to nature, thus producing the effect of a perfect fit of the glove, while at the same time any possible minor defects in the nail may be concealed.

Having described my invention, what I claim as new, and desire to secure by Letters Patent, is—

The design for a glove as herein shown and described.

DANIEL H. MURPHY.
